UNITED STATES PATENT OFFICE.

CARROLL W. ALLEN, OF NEW ORLEANS, LOUISIANA.

DESIGN FOR A BOX OR LIKE ARTICLE FOR DRY-FOOD PRODUCTS.

Application filed January 27, 1926. Serial No. 16,290. Term of patent 14 years.

To all whom it may concern:

Be it known that I, CARROLL W. ALLEN, a citizen of the United States, residing at New Orleans, parish of Orleans, and State of Louisiana, have invented a new, original, and ornamental Design for a Box or like Article for Dry-Food Products, of which the following is a specification, reference being had to the accompanying drawings, forming a part thereof.

The figure is a side elevation of the box with the parts assembled in the closed position.

I claim:

The ornamental design for a box or like article for dry food products as shown.

In testimony whereof I affix my signature.

CARROLL W. ALLEN.
